UNITED STATES PATENT OFFICE.

FRANK H. FARNHAM, OF CINCINNATI, OHIO.

APPARATUS FOR RAISING AND LOWERING BUGGY-TOPS.

SPECIFICATION forming part of Letters Patent No. 536,864, dated April 2, 1895.

Application filed March 28, 1894. Serial No. 505,490. (No model.)

To all whom it may concern

Be it known that I, FRANK H. FARNHAM, a citizen of the United States, residing at Cincinnati, in the county of Hamilton and State 5 of Ohio, have invented a new and useful Improvement in Apparatus for Raising and Lowering Buggy-Tops, which improvement is fully set forth in the following specification and accompanying drawings, in which—

10 Figure 1 is a side view of my invention, with the top shown in dotted lines in its lowered and folded position. Fig. 2 is a detail showing more particularly the rock-shaft actuating lever for conveniently lowering the 15 top.

My invention pertains to improvements in apparatus for raising and lowering buggy and carriage tops, and its object is to provide a simple, durable and effective device whereby 20 the top may be easily drawn up or down by the driver while in his seat, without stopping the vehicle or releasing the driving reins.

The invention consists of a simple and inexpensive attachment to the body of the vehicle as generally constructed.

The peculiar advantages and operation of the device will be readily understood by referring to the accompanying drawings, in which—

30 A designates the body of the vehicle provided interiorly with the ordinary iron stays 2, side rails 3, and back stays 4. A rock shaft 5, which is normally concealed from view by the back cushion, extends across the inner 35 side of the back of the vehicle body and is journaled in the side rails 3. The outer ends of this shaft are squared and closely fitted within corresponding apertures in the lower ends of the side braces 6. The upper section 40 of each of the side-braces 6 forms the stem

or vertical portion of a T shaped stay 9 applied to each side of the top and pivoted at its center to the middle bow thereof and at the ends of its top, cross, or horizontal, portion to the front and rear bows, respectively. 45 This top cross or horizontal portion is provided with folding sections 8 and 10 jointed as shown thereto to fold or flex reversely as the top is lowered, to permit simultaneously also the compact folding of the top as outlined in dotted lines in Fig. 1. An operating lever 7 is attached to the rock shaft by a set screw or other suitable means. It will be observed that when the top of the vehicle is in an erect position the lever lies horizontally 50 across the end of the seat and within convenient reach of the right hand of the driver, who can easily and gradually lower the top by raising the lever to the position shown in Fig. 1. 55

What I claim as new is—

The combination of the rock-shaft journaled upon the vehicle-body and having applied thereto an actuating lever, the approximately T-shaped, jointed stays having their 65 lower ends fixed to said shaft and the arms of their top cross-pieces jointed to sections adapted to fold reversely and pivoted to the front and rear bows of the top, said top cross-pieces being centrally pivoted to the middle 70 bows of the top, whereby the top is adapted to be simultaneously lowered and folded, substantially as set forth.

In testimony that I claim the foregoing I have hereunto set my hand, this 22d day of 75 March, 1894, in the presence of witnesses.

FRANK H. FARNHAM.
